Graded sand, gravel, or like material, and the like, may be sorted into a number of approximately equal sizes.

UNITED STATES PATENT OFFICE

2,386,579

GRADING MACHINE

Delbert Wheeler, Sioux Falls, S. Dak.

Application July 27, 1942, Serial No. 452,397

2 Claims. (Cl. 209—314)

This invention relates to grading machines and has for its object to provide such a machine so constructed that sand, gravel, crushed stone and the like may be sorted into a number of approximately equal sizes.

Another object of the invention is to provide in a grading machine a series of stepped screens and means for simultaneously agitating all of said screens.

Another object of the invention is to provide in a grading machine a plurality of inclined stepped screens and a box of varying depths in which said screens are mounted.

A further object of the invention is to provide a screening box mounted upon a plurality of eccentric agitator shafts.

A still further object of the invention is to provide a grading machine comprising a box having a series of stepped screens each succeeding screen being of a finer mesh than the preceding one, and a counter weight for said box.

Another object of the invention is to provide in a grading device, a sieve box and agitators at both ends thereof.

Another object of the invention is to provide in a grading machine a screen box of varying depths carrying a plurality of screens of varying mesh and a plurality of delivery chutes from each screen.

With the above and such other objects in view as may hereinafter more fully appear, I have invented the machine described in the following specification and illustrated in the accompanying drawings in which:

Figure 1 is a top plan view of my improved machine;

Figure 2 is a side elevational view thereof;

Figure 3 is a section on line 3—3 of Figure 1;

Figure 4 is a section on line 4—4 of Figure 1;

Figure 5 is a section on line 5—5 of Figure 1;

Figure 6 is a section on line 6—6 of Figure 3;

Figure 7 is a section on line 7—7 of Figure 3; and

Figure 8 is a diagrammatic view of a chute arrangement.

Like reference characters indicate like parts throughout the following specification and in the several views in the drawings in which 1 indicates my improved grading machine as an entirety. 2 is sieving box having its lower end 3 much deeper than its upper end 4; its side walls 5 and 6 gradually tapering from its lower end 5' to its upper end 6'. Mounted in this box is a series of screens 7, 8, 9 and 10, one below the other in stepped relation from its upper end to its lower

end. Each upper screen is so arranged as to pass its ungraded load on to the next lower screen in a manner to hereinafter be explained. Below each of the screens, except the last screen 10, are located chutes 11, 12 and 13, the bottom walls 14 and 15 of which are hipped so as to incline toward said side walls 5 and 6 respectively. Mounted under each screen 7, 8, etc. are receiving plates 16, 17 etc., upon which the screened material from the screen above passes, and as the lower ends of these plates project over the next lower screen, the material thereon is joggled down onto said next screen, while the material remaining upon the screen is joggled off onto the inclined walls of the chutes 11, 12 etc., the lower ends of which project through openings 18, 19, and 20 and 18', 19' and 20' in said side walls 5 and 6.

Depending from the box 2 and securely fixed thereto are roller bearing journal boxes 23, 24, 25 and 26 for the vibrator shafts 27 and 28, the former located transversely of the box at its upper end 29 and the latter located near the lower end in the same manner. The outer ends 27' and 27'' of shaft 27 are supported in bearings 31 and 32 mounted on the frame timbers 33 and 34, and the outer ends 28' and 28'' of shaft 28 are supported in bearings 35 and 36 mounted on said timbers 33 and 34. The shaft 27 is provided with three eccentric enlargements 37, 38 and 39, the former and latter of which operate in the bearings 23 and 24 respectively. The shaft 28 is also provided with three eccentric enlargements or cams 40, 41 and 42, the first and last of which operate in the bearings 25 and 26. The eccentric cams 38 and 41 are located centrally of said shafts 27 and 28 and support roller bearings 43 and 44 in which they operate, and to which latter bearing members is secured a counterweight 45 for the sieve structure.

Mounted fixedly on the free end 28' of shaft 28 is a power drive pulley 46, and on its free end 28'' is keyed a bevel gear 47 meshed with a like gear 48 fixed on the transmission shaft 49 supported upon bearings 50 and 51 mounted on the box timber 2' by means of bracket bearings 52 and 53. Fixed on the upper end of shaft 49 is a mitre gear 54 meshed with a similar gear 55 fixed on the outer end of shaft 27. Any material remaining on the last screen 10 is deposited from its end 55. Eccentric shafts 27 and 28 so turned and timed as to give the screen box and counter weight a circular throw. The counterweight is always in a position to balance the weight of the screen box.

While I have designed the above described

grading machine especially for sand, gravel, crushed rock, etc. I have it so arranged that it is just as applicable for the grading of many other products such as nuts, fruits and certain vegetables including tomatoes and in the latter case I use a cord screen with a cotton fabric receiving plate located under the screens to avoid bruising the vegetables.

Having now described my invention, that which I claim to be new and desire to procure by Letters Patent is:

1. In a grading machine, in combination, a pair of spaced stationary frame members, a pair of spaced horizontal shafts extending transversely of and journaled on said frame members, said shafts being arranged in different horizontal planes, each of said shafts having outer eccentrics near the ends thereof and a single inner eccentric midway between the outer eccentrics, the inner eccentrics of said shafts being displaced 180° relative to the outer eccentrics, a screening device including an inclined box having a pair of transversely aligned journal boxes fixed on the bottom thereof near each end of

the same, each pair of journal boxes receiving the outer eccentrics of one of said shafts, an elongated counterweight bar having spaced bearings fixed thereon and receiving the intermediate eccentrics of said shafts, and means for rotatably driving said shafts simultaneously at the same rate of speed and in the same direction.

2. In a grading machine, a gyratory screening device including a forwardly inclined elongated box having a series of horizontal screens mounted therein in stepped relation with the forward end portion of each screen projecting over the rear end portion of the next screen therebelow, a forwardly inclined chute plate mounted below the rear portion of each screen and projecting over the rear end of the next lower screen, a transverse discharge chute mounted at the forward end of each screen to receive the material which fails to pass through said screen, each transverse chute having oppositely and outwardly inclined half-portions projecting through opposite sides of the box, and means to positively gyrate said screening device in a vertical path.

DELBERT WHEELER.
